UNITED STATES PATENT OFFICE.

JOSEPH HAAS, OF NEW YORK, N. Y.

FURNITURE.

967,903.

Specification of Letters Patent. Patented Aug. 23, 1910.

Application filed December 2, 1908. Serial No. 465,689.

To all whom it may concern:

Be it known that I, JOSEPH HAAS, a citizen of the United States, residing in New York, borough of Brooklyn, county of Kings, and State of New York, have invented certain new and useful Improvements in Furniture, of which the following is a specification.

This invention relates to certain improvements in combination furniture, and has for its object to provide an article of furniture of a simple and comparatively inexpensive nature, and of a strong and substantial construction in the form of a chair, having certain features of novelty and improvement rendering it readily convertible for other purposes, such for example, as an ironing board or table, or as a step-ladder.

The invention consists in certain novel features of the construction, and combinations and arrangements of the several parts of the improved combination chair, whereby certain important advantages are attained, and the device is rendered simpler, less expensive, stronger, more compact, and otherwise better adapted and more convenient for use, all as will be hereinafter fully set forth.

The novel features of the invention will be carefully defined in the claim.

In order that my invention may be the better understood, I will now proceed to describe the same with reference to the accompanying drawings, wherein—

Figure 1 is a perspective view of a combination chair embodying my improvements; Fig. 2 is a perspective view of the device, showing the same converted for use as an ironing board or table and extended to its maximum length; Fig. 3 is a perspective view showing the device converted for use as a step-ladder, and—Fig. 4 is a view similar to Fig. 2, but showing the device adjusted to afford a shorter ironing board or table.

As herein shown, the improved combination chair comprises upright rear side members 10, 10, formed from elongated strips or pieces of flattened material of sufficient length to produce rear legs α^1 , and back supports α integral with said rear legs. These members 10, 10 are spaced apart from each other to produce between them a chamber or compartment extended the full height of the chair and its back, and are connected or tied together at their lower ends by a transversely extended flattened brace or rung 17, which affords a bottom for said compartment or chamber.

A, A represent the forward legs of the chair, each of which is formed in two sections 12 and 13, the meeting edges of which are adapted to be fitted flush one upon the other, the rearmost leg sections 12, 12 or those adjacent to the rear legs α^1 , being connected securely with said rear legs by means of horizontal rearwardly directed upper and lower braces or strips 11 and 18, the former of which afford seat supports upon which are rested and secured the opposite ends of a rear seat section 14, which is extended forwardly from the chamber or compartment between the upright rear members 10, 10, and has at its forward edge hinge connection, as shown at 16, with the rear edge of a forward seat section 15, secured upon the upper ends of the forward leg sections 13, 13, and adapted, when the structure is in use as a chair, as shown in Fig. 1, to be extended in front of and flush with said rear seat section so as to afford a substantial continuation thereof.

The line of division between the meeting edges of the front and rear sections 12 and 13 of the forward legs A, A, is extended in a direction downwardly and forwardly inclined with respect to the rear members 10, 10, and at suitable points in the length of said legs A, A, transverse step members 19, 19^a, and 20, 20^a are extended between the respective leg sections 12, 12 and 13, 13, said members 19, and 19^a registering with each other to produce a lower step when the device is adjusted as shown in Fig. 1, and the members 20 and 20^a also registering with each other to produce an upper step, whereby it will be seen that the structure is capable of use as a short step ladder even when adjusted for use as a chair. The construction is also such that the rear leg sections 12, 12 with the rear step members 19 and 20 extended between them, and the rear seat section 14 at their upper ends form a lower ladder section, while the forward leg sections 13, 13, with the seat members 19^a and 20^a extended between them and the forward seat member 15 secured upon their upper ends afford an upper ladder section which is adapted, when required, to be folded upwardly and rearwardly to the position shown in Fig. 3, so as to afford a step ladder of greater height, the forward seat section 15 folding flush upon the top surface of the rear seat section 14, so as to afford a substantial support for the upper ladder

section, and the free ends of the forward leg sections 13, 13 bearing firmly against the forward edges of the back supports *a*, *a* afforded by the upper ends of the upright rear members 10, 10.

21 represents hooks carried by the free ends of the forward leg sections 13, 13 and capable of engagement, when the structure is in use as a chair, with eyes 22 upon the rear sections 12, 12, and also adapted, when the device is adjusted as shown in Fig. 3, for engagement with similar eyes 23 upon the back supports *a*.

In addition to its use as a chair and as a step ladder, the device embodying my improvements is also capable of employment as an ironing board or table, for which purpose an ironing board D is provided, the same being herein shown as made in the conventional form, but centrally and transversely divided into two sections *d* and *d*¹ pivotally connected at their meeting ends by means of hinges 24, the leaves of which are secured upon the under surfaces of spaced battens 27, and 27^a secured upon the undersides of the respective sections *d* and *d*¹, as clearly seen in Figs. 2 and 4, the construction being similar to a rule joint in order that when said sections are extended end to end, to afford an ironing board or table of maximum length, as shown in Fig. 2, the extremities of said sections and of their respective spaced battens are adapted to abut upon each other in order to afford a strong and rigid structure, and prevent sagging of the central part of the board.

The wider or main section *d* of the ironing board member D is provided, adjacent to its wider or head end, with a cleat D¹ secured upon and extended transversely across its under surface, and the extremities of this cleat D¹ are made to project beyond the opposite edges of said ironing board section *d*, and are made rounded and adapted for pivotal engagement in rounded openings or perforations produced in the upper parts of the back supports *a*, afforded by the upper ends of the flattened rear members 10, 10, as clearly shown at 25, in Figs. 2, 3 and 4, the said ironing board section *d* being of a width to fit readily between said back supports *a*, whereby it will be seen that an effective pivotal connection is afforded between the ironing board member D and said rear supports 10, 10, adapted to securely support the larger or head end of said ironing board member when the same is extended in horizontal position, as shown in Fig. 2, but capable of operation to permit said member, when its sections *d* and *d*¹ are folded one beneath the other, to be swung pivotally upward and rearwardly and dropped over back of the seat portion of the chair, and housed within the vertically extended chamber or compartment between

the flattened rear members 10, 10, as illustrated in Figs. 1 and 3, so that the larger or head section *d* of said member D is extended up above the seat B of the chair and between the members 10, 10, to produce a back for the chair.

29 represents an elongated hook pivoted upon one of the rear members 10 and adapted, when the ironing board member D is folded and housed between the spaced members 10, 10, to be extended transversely across the rear surface of the folded member D and engaged with an eye 30 carried by the opposite member 10, in such a way as to securely hold said ironing board member D against pivotal movement when in its compacted position. Since the sections *d* and *d*¹ of the member D will usually be padded, as usual for use in ironing, such padding will afford a cushion for the chair back when the member D is compacted.

25^a represents a leg or support pivotally connected at 26 with the underside of the free end of the terminal or narrower section *d*¹ of the ironing board member D, and adapted, when the sections *d* and *d*¹ are extended end to end, as shown in Fig. 2, to be dropped into vertical position with its lower end resting upon the floor in order to support the end of the member D wherewith said leg or support is connected, and when the member D is to be folded or compacted, this leg or support 25^a is adapted to be folded flush upon the underside of the section *d*¹, as shown in Fig. 4, and its free end is of such a width as to be adapted to be received between the spaced battens 27, 27 at the opposite end of said section *d*¹, in which position said leg or support may be securely held, if desired, by means of a hook or fastening 28, carried by the free end portion of the leg and engaging the hinged end of the section *d*¹, said leg being of such length as to project beyond the hinged end when the sections are folded. When said leg or support 25^a is adjusted to this position, the section *d*¹ of member D may be dropped vertically so that its free end may rest upon the floor, as shown in Fig. 4, thereby affording a short ironing board or table, and when it is desired to completely fold the member D, said terminal section *d*¹ is capable of being folded against the underside of the section *d*, in position to snugly house the leg or support 25^a between the sections *d* and *d*¹ in order that the same may not be in the way when the member D is housed between the rear members 10, 10 as above described.

From the above description of my invention it will be seen that the improved combination chair constructed according thereto is of an extremely simple and comparatively inexpensive nature, and is particularly well adapted for use by reason of the strength and rigidity of its construction and of the

compactness with which the several parts fold together when not required for use, and it will also be obvious from the above description of my improvements, that the device is susceptible of some modification without material departure from the principles and spirit of the invention, and for this reason I do not desire to be understood as limiting myself to the precise formation and arrangement of the several parts herein set forth, in carrying out my invention in practice.

Having thus described my invention, what I claim and desire to secure by Letters Patent is—

A combination chair having spaced upwardly extended back supports, a main ironing board section one end of which is pivotally connected with said back supports, a

terminal ironing board section, battens carried by the opposed ends of the main and terminal sections, said battens being spaced, hinged connections for the sections secured to the battens, a supporting leg pivoted to the terminal section, said leg being of such length as to project between the battens and beyond the hinged end of the terminal section when the parts are compacted, and a fastening means carried by the free end portion of the leg to contact with the hinged end of the terminal member.

In witness whereof I have hereunto signed my name, in the presence of two subscribing witnesses.

JOSEPH HAAS.
